UNITED STATES PATENT OFFICE.

JOHN WILSON ORROCK, OF WESTMOUNT, QUEBEC, CANADA.

FLANGEWAY-GUARD.

1,384,333.

Specification of Letters Patent. Patented July 12, 1921.

Application filed September 8, 1920. Serial No. 409,025.

To all whom it may concern:

Be it known that I, JOHN W. ORROCK, subject of the King of England, residing at Westmount, in the Province of Quebec and 5 Dominion of Canada, have invented certain new and useful Improvements in Flange-way-Guards, of which the following is a specification.

This invention relates to an improvement 10 in flange-way guards for railway rails to be used at road or grade crossings and in shop floors and the like where the floor is level with the top of the rail and it is necessary to provide a groove or channel for 15 wheel flange clearance and to protect the floor from being damaged by vehicles passing transversely over the rails.

A primary object of the invention is to 20 provide a guard adapted to be carried entirely by the rail which has the advantage of avoiding interference with tie plates and track fastenings, and furthermore keeps the rail as it moves under the influence of passing 25 wheel loads. Heretofore, it has been the general practice to attach or support the guard directly or indirectly on the tie as distinguished from a support which solely 30 engages the rail and is free from all connection with the ties or track fastenings. On the contrary, the present invention contemplates the provision of a rail carried flange-way guard which will effectively 35 function as an integral part of the rail after application thereto.

A further object of the invention is to provide a simple and practical means for clamping the guard directly to the rail at varying intervals that may be conveniently selected 40 with reference to the tie and joint spacing to thereby enable the installation to be easily and quickly made with a minimum of labor, while at the same time maintaining a low subsequent cost of maintenance which materially enhances the practical value and 45 utility of the improvement.

With the above and other objects in view which will more readily appear as the nature of the invention is better understood, 50 the same consists in the novel construction, combination and arrangement of parts hereinafter more fully described, illustrated and claimed.

A preferred and practical embodiment of the invention is shown in the accompanying drawings, in which:

Figure 1 is a side elevation of a portion of the improved flange-way guard applied to a rail, and illustrating the relative spacing of the stands or supports therefor.

Fig. 2 is a vertical cross-section of an installation of the present improvements, clearly showing the means for clamping or holding the guard supporting stands to the running or gage side of the rails.

Fig. 3 is a top plan view of the construction shown in Figs. 1 and 2.

Fig. 4 is a detail perspective view of one of the guard supporting stands.

Fig. 5 is a plan view of the flared end- 70 guard section.

Similar reference numerals designate corresponding parts throughout the several figures of the drawings.

In the execution of the invention, the applicant seeks to provide a flange-way guard which departs from the usual practice customarily followed in installations of this character, by providing a device which is carried entirely by and with the rail. That 80 is to say, it is proposed to avoid connecting any part of the device with the tie or other element of the road bed, because of the existence of the well known wave motion of the rails under the influence of passing 85 wheel loads which causes the rail to move relatively independent of its fastenings, and in installations wherein the guard rests on or is spiked to the ties there is a differential movement between the guard and the rail 90 which frequently produces precisely the results intended to be avoided by provision of the wheel flange-way.

Accordingly, as will be apparent from the drawings it is proposed to provide a substantially troughed or channeled guard member 95 1 that is adapted to be fitted to the running side of the rail R and so formed as to provide a relatively long outside flange 2, a relatively short inside flange 3, and an intermediate floor portion 4. In the case of the flange 2, it will be observed that the same is preferably inclined upwardly and terminates as at 2^a, flushly with the grade of the road crossing, while the flange 3 is 105 beveled as at 3^a to fit snugly beneath the in-

clined under side of the head of the rail R. The end section of this guard is preferably flared at f as shown in Fig. 5.

The relatively flat floor portion 4 of the guard may be conveniently utilized to provide a plurality of fastening receiving openings 5, spaced on predetermined centers, to readily accommodate various road conditions and requirements of installation with respect to the placing and fitting of the novel guard supports or stands designated generally as S. That is to say, the stands S, by reason of the plurality of points of attachment to the guard may be placed at any suitable and convenient interval, as between the ties or joints, to give the desired supporting effect to the guard.

In connection with the stands S it is to be observed that each essentially includes means for supporting the guard, and means for securely gripping the base of the rail to hold the stand in place. To this end it is proposed to make the stand proper in any desired way, one example being a suitable metallic plate which may be conveniently bent and cut to provide the necessary elements for facilitating the seating of the same on the base flange of the rail. That is to say, it is proposed to provide a body element 6 having the relatively flat crown or table portion 7 for supporting the floor of the guard, while the inner end 8 of the body extends downwardly in an inclined plane to provide the rail flange engaging foot 9 for resting upon the base flange of the rail adjacent the web thereof. The opposite sides of the body 6 of the stands are preferably formed with the metal tongues 10 which are bent downwardly to engage the inclined upper face of the base flange of the rail. It will thus be apparent that through the coöperation of the tongues 10 and the foot 9, the body 6 of the stand is effectively braced when positioned on the upper side of the base flange of the rail. And, in order to maintain the stand in its proper position, the depending skirt portion 11 of the body 6 is provided with an opening 12 for receiving the threaded end 13 of a securing bolt 14, whereby the nut 15 on the said threaded portion 13 may act in opposition to the hooked end or head 16 of the bolt which engages over and about the base flange of the rail opposite that to which the flange-way guard is applied.

From the foregoing it is believed that the manner of application will be apparent, but by way of further explaining the manner of installation it may be pointed out that the troughed guard member 1 may be conveniently supported on the table portion 7 of the stands S at any desired point along its length by passing a suitable bolt B or equivalent coupling element in one of the openings 5 in the floor of the guard and

the opening 7^a in the table portion 7. Upon determining the desired location of the stands S with reference to the guard, and fitting the same in position at the gage side of the rail, the tie or fastening bolts 14 may be placed in the position shown in Fig. 2, whereby the tightening of the nut 15 will firmly anchor the stand in place by shifting the bolt transversely across the under side of the rail base in such a manner that the hook or head portion 16 thereof will firmly bind or grip the opposite rail flange in a manner which will be obvious.

Also from Fig. 2 of the drawings, more particularly, it will be observed that the assembled structure provides through the medium of the flange 3 of the guard member, the foot 9 and tongues 10 of the stand, such an arrangement, located substantially within the fishing space of the rail, that when the fastening bolt 14 or its equivalent is screwed into position it will have the effect of causing the stand to ride upwardly on the inclined face of the base flange of the rail and tightly wedge the connected guard and stand between the underside of the rail head and the upper inclined face of the rail flange. Thus, the entire structure is rigidly supported in position in a thoroughly practical and efficient manner.

Without further description it is thought that the many features and advantages of the invention will be readily apparent, and it will of course be understood that various changes in the proportion, and minor details of construction may be resorted to without departing from the spirit of the invention or scope of the appended claims.

I claim:—

1. A flangeway guard including in combination with the rail, a channeled guard member offset from the gage side of the rail and having an engagement beneath the head thereof, and a supporting member fastened to the rail base and arranged to sustain the guard member in position.

2. A flangeway guard including in combination with the rail, a guard element located at the gage side of the rail, and means having an engagement with both base flanges of the rail for holding the said guard in position.

3. A flangeway guard including in combination with the rail, a guard element located at the gage side of the rail, and means having a supporting engagement with a base flange of the rail for holding the said guard in position.

4. A flangeway guard including in combination with the rail, a guard element located at the gage side of the rail and having a plurality of spaced attachment openings, and supporting devices for the guard adapted to be located at any one of the said spaced openings and having means for en-

gaging a base flange of the rail to hold the guard in position.

5. A flangeway guard including in combination with the rail, a guard located at 5 the gage side of the rail, a plurality of guard supporting stands having a supporting engagement with the upper inclined face of one of the base flanges of the rail, and means having a holding engagement 10 with a base flange of the rail for maintaining said supporting stand in position.

6. In a flangeway guard, the combination with the rail of a guard member adapted to be located at the gage side of the rail 15 head, a plurality of supporting stands detachably engaged with the guard member and resting upon the upper inclined face of one of the base flanges of the rail, and a bolt for engaging with the support for the 20 guard member and also with the opposite base flange of the rail to hold the said supporting stand in place.

7. In a flangeway guard, the combination with a troughed guard member having a 25 portion fitting beneath the rail head, and a stand for engaging with the guard and the upper inclined face of the base flange of the rail, and means for drawing said stand transversely of the rail to tightly wedge the 30 portion of the guard engaging beneath the rail head against the latter as the stand rides up the said inclined face of the base flange.

8. In a flangeway guard, the combination 35 with the rail, of a guard member and support therefor each having portions fitting within the fishing space of the rail, and means for advancing the guard and its support into the fishing space toward the web 40 of the rail to secure the same in position.

9. In a flangeway guard, the combination with the rail, of a guard member of trough-shaped cross section and having one wall thereof of less height than the other and 45 also having an intermediate connecting wall

provided with openings, and means carried by the base of the rail and engaging with the guard at one of the openings for holding the same in position at the gage side of the head of said rail.

50

10. In a flangeway guard, the combination with the rail, of a guard member of trough shaped cross section and having one wall thereof of less height than the other and also having an intermediate connecting wall, and means carried by the base of the rail and engaging with the guard for holding the same in position at the gage side of the head of said rail.

55

11. In a flangeway guard, the combination with the rail, of a troughed guard member, and a stand including a body having a relatively horizontal portion for supporting the guard member and a downwardly inclined portion presenting a foot 60 for engaging with the inclined upper surface of the base flange of the rail adjacent the web thereof, an inclined tongue formed from opposite edges of the body of the stand for engaging the upper inclined face 65 of the base flange of the rail adjacent the edge thereof, and a device for engaging with the body of the stand for securing the same in position on the rail.

60

12. In a flange-way guard, the combination with the rail, of a continuous guard member adapted to be positioned at the gage side of the rail, a plurality of supports adapted to be selectively positioned along the guard member, and means having a 70 holding engagement with a base flange of the rail for maintaining said supports in 75 position.

In testimony whereof I hereunto affix my signature in the presence of two witnesses. 80
JOHN WILSON ORROCK.
